ATTORNEY.

UNITED STATES PATENT OFFICE

SAMUEL B. BLEADON, OF SAN FRANCISCO, CALIFORNIA

CONTAINER FOR TOOTHBRUSHES

Application filed February 18, 1930. Serial No. 422,862.

The present invention relates to improvements in containers or receptacles and has reference more particularly to a tooth brush container.

One of the important objects of the present invention is to provide a container for the brush portion of a tooth brush when the latter is not in use for the purpose of protecting the bristles from collecting germs, dust and the like.

A salient object of the present invention is to provide a sanitary tooth brush container that is constructed of destructible material so that after the container has been used, the same can be thrown away and a fresh container brought into use, the container being constructed of such material as to render the same inexpensive in its manufacture.

Still another object is to provide a sanitary tooth brush container of the above-mentioned character wherein an absorbent lining is arranged within the container so that any moisture remaining on the bristles of the brush when inserted in the container will be evaporated thereby tending to maintain the best sanitary conditions.

Other objects and advantages of the invention will become apparent from the following description when taken in connection with the accompanying drawing.

In the accompanying drawing wherein like reference characters indicate corresponding parts throughout the several views:

Figure 1 represents a side elevation of my improved container showing a tooth brush inserted therein.

Figure 2 is a longitudinal sectional view taken approximately on the line 2-2 of Figure 1.

Figure 3 is a vertical sectional view taken substantially on the line 3-3 of Figure 2 looking in the same direction of the arrows; and

Figure 4 is a detail perspective view of the removable lining per se.

In the drawing wherein for the purpose of illustration is shown the preferred embodiment of my invention, the numeral 1 designates generally the container embodying my invention, the same being preferably formed

of paper and constructed in such a manner as to form a bag-like receptacle that is open only at one end.

Arranged within the container 1 is the lining 2 formed of any suitable absorbent material and attention is now directed to Figure 4 of the drawing wherein the lining is shown in detail. It will be observed upon referring to this particular figure that the lining is formed from a single blank of material folded 55 longitudinally to provide the overlapping folds 3 and 4 and these folds are cemented together at only one point as at 5 adjacent one end of the lining so that the lining will be in the form of an envelop open at its re- 65 spective ends with the major portions of the overlapping portions of the folds not being cemented together.

The absorbent lining 2 is inserted within the paper container 1 and if desired, the inner 70 end portion of the lining may be cemented to the adjacent portion of the container. In inserting the lining, the end which has its overlapping folds disconnected is inserted first. Consequently the connected portions of 75 the folds are disposed immediately adjacent the mouth of the receptacle, so that the folds can be very easily and conveniently separated upon opening of the receptacle, and thereby facilitate removal of the brush for use. 80

If desired, the absorbent lining may be saturated with a suitable antiseptic compound so that a thoroughly sanitary condition will be preserved.

When the brush part of the tooth brush A 85 is inserted within the container as indicated in Figures 1, 2 and 3, the open end of the container may be closed in any suitable manner and in the present instance, I have shown the container as being closed by folding over 90 the corner portion.

The lining 2 will tend to absorb any moisture present on the bristles of the brush and by encasing the brush in the manner as proposed, the same will be protected against 95 germs and other foreign matter when not in use.

The container 1 may have any suitable advertising indicia printed on the outer face thereof and when the tooth brush is to be 100

used, the same is removed from the container after which the container is destroyed and a fresh container is brought into use when the tooth brush is again to be placed away.

- 5 The construction of a sanitary tooth brush container of the above-mentioned character renders the same very inexpensive and at the same time efficient in carrying out the purposes for which it is designed.
- 10 While I have shown the preferred embodiment of my invention, it is to be understood that minor changes in the size, shape and arrangement of parts may be resorted to without departing from the spirit of the invention or the scope of the appended claim.

What I claim as new is:

- 20 A tooth brush container comprising a normally flat bag-like receptacle of uniform width throughout and open at one end to receive the head of the brush, an envelope-like lining of absorbent material within the receptacle and open at both ends, said lining being formed from a blank of material folded to provide overlapping folds having their corresponding upper corners connected together and free for the remaining portions of their length, and the corners of the open end of the receptacle and the adjacent corners of said lining being folded on one side of the receptacle to snugly close the latter about the handle of the brush.
- 25
- 30

In testimony whereof I affix my signature.

SAMUEL B. BLEADON.
